CLAIM

The ornamental design for a combined audio and video apparatus as shown and described.

DESCRIPTION

1. Combined audio and video apparatus

1.1 : Perspective

1.2 : Front

1.3 : Back

1.4 : Left

1.5 : Right

1.6 : Top

1.7 : Bottom

The broken lines shown in the drawings depict portions of the combined audio and video apparatus that form no part of the claimed design; The parallel thin lines and the radial thin lines in the representation represent contours only and do not illustrate an ornamentation or decoration on the surface of the product.

1 Claim, 7 Drawing Sheets
